UNITED STATES PATENT OFFICE.

HERBERT F. PORTER, OF NEW YORK, N. Y.

GRATE.

Application filed February 15, 1928. Serial No. 254,534.

This invention relates to improvements in grates and has more specifically to do with an improved grate bar.

An object of the invention is to provide a 5 grate bar having a plurality of parallel webs spaced apart so that ashes may drop between the webs, and said webs provide a plurality of points of support for independent, removable, fuel-supporting bars or elements.

10 An assemblage of this kind has many advantages, some of which may be enumerated as follows:

The bar itself is strong and durable and in 15 tilting action exerts a leverage on the elements supported thereby which is greater than an average bar, and, furthermore, there is less liability of breakage than there would be if the elements were supported centrally by a single bar.

20 The webs may be narrower than a single bar so that ample space is provided for the ashes to fall through and not lodge on the bar, and, furthermore, the webs, particularly the center web, is deflected or tapered so that 25 no ashes can rest thereon.

With these and other objects in view, the invention consists in certain novel features of construction and combinations and arrangements of parts, which will be more fully 30 hereinafter described and pointed out in the claims.

In the accompanying drawings—

Figure 1 is a view showing the bar in plan, also showing a fuel-supporting bar or 35 element in plan, and another bar or element in section;

Figure 2 is an end view of Figure 1;

Figure 3 is a view in transverse section on the line 3—3 of Figure 1;

40 Figure 4 is a view in transverse section on the line 4—4 of Figure 1;

Figure 5 is a fragmentary view in section, similar to Figure 3, illustrating how one of the fuel-supporting bars or elements may be 45 retained on the grate bar when the assemblage of elements is completed on the bar.

My improved grate bar is indicated generally by the reference character A, and comprises a central longitudinal web 1 integrally 50 connected by lateral ribs 2 with webs 3, 3. The webs 3, 3 are parallel to the central web 1 and all of said webs are integral with end plates 4, said end plates having trunnions 5 thereon for pivotally mounting the grate bar 55 and allowing it the required support, and on

one of said plates a depending crank arm 6 is provided for the attachment of means to rock the bar.

While I have illustrated my improved bar as having three longitudinal webs it is of 60 course to be understood that I do not wish to be limited to the specific number but believe an arrangement of three is a preferable one.

While I have illustrated my improved bar as having three longitudinal webs it is of 60 course to be understood that I do not wish to be limited to the specific number but believe an arrangement of three is a preferable one.

The bar A is adapted to support a series 65 of fuel-supporting bars or elements 7 which are positioned transversely of the grate bar and are supported on all three webs of the grate bar. These elements 7 have at opposite sides spaced teeth, and the spaces between the 70 teeth are of approximately the same size as the teeth; and the upper portions of said bars are slightly spaced apart so as to give a maximum of air draft and yet properly support the fuel.

75 My improved grate is especially adapted for supporting fine fuel and hence it is important that the fuel be prevented from passing through the grate yet it is desirable that a maximum air space be left for the draft.

80 The elements 7 are provided with depending tongues 8 at their ends, having enlargements 9 thereon which fit under outwardly projecting flanges 10 on the outside webs 3 of bar 8 so as to hold the elements 7 against 85 displacement relative to the bar.

The elements 9, as shown most clearly in Figure 1, are of such length that when they abut one against the other they properly space the elements 7, and the flanges 10 on the 90 bar A have recesses 11 therein of a width sufficient to accommodate the enlargements 9 of one grate element 7, so that the elements may be inserted on the bar at this point and then moved longitudinally out of the bar until the 95 bar has its quota of fuel-supporting elements.

The last fuel-supporting element may be equipped with a bendable tongue or finger 12, as shown in Figure 5, so as to be bent under a web 3 to hold this element on the grate bar. 100

I would call particular attention to the cross sectional shape of the webs 1 and 3, as shown clearly in Figure 3 of the drawings. It will be noted that the central web 1 has its upper edge of inverted V-shape in cross section so as to present a sharp point of contact to the elements 7 and deflect any ash which may fall against the same between the webs and prevent the possibility of the ash accumulating on this web. The side webs 3, 3 are 105 110

preferably made with a slightly wider upper surface but they too are deflected at their side portions so as to shed the ash.

It will thus be noted that with a bar of this type there is no wide surface on which the ash may accumulate such as is true of grate bars in general use, and hence the accumulation of said ash cannot interfere with the draft nor choke the grate.

10 Furthermore, it will be noted that the grate bar provides a plurality of points of support, one at the center and others adjacent the respective ends of the fuel-supporting elements 7, so that when the grate bar is rocked a direct lifting action is had under the fuel-supporting elements 7 adjacent their ends.

Various changes and alterations might be made in the general form of the parts described without departing from the invention and hence I do not limit myself to the precise details set forth but consider myself at liberty to make such changes and alterations as fairly fall within the spirit and scope of the appended claims.

25 I claim:

1. A grate bar, comprising three parallel webs spaced apart, end plates integrally con-

necting said webs, ribs integrally connecting said webs intermediate their ends, the outer webs having flanges thereon with recesses in said flanges, fuel-supporting elements on said webs, tongues on the elements, and enlargements on the tongues engaging under the flanges of the outside webs, and having entrance to said position through said recesses.

2. A grate bar, comprising three parallel webs spaced apart, end plates integrally connecting said webs, ribs integrally connecting said webs intermediate their ends, the outer webs having flanges thereon with recesses in said flanges, fuel-supporting elements on said webs, tongues on the elements, and enlargements on the tongues engaging under the flanges of the outside webs and having entrance to said position through said recesses, said enlargements of a length whereby when they engage each other the elements will be spaced apart.

Signed at New York, in the county of New York and State of New York, this 11th day of February A. D. 1928.

HERBERT F. PORTER.
